(57) CLAIM

We claim the ornamental design for a folding, padded portable seat with curved back, bleacher hooks and snap strap, as shown and described.

DESCRIPTION

FIG. 1 is a perspective view of a folding, padded portable seat with curved back, bleacher hooks and snap strap showing our new design;

FIG. 2 is a right side elevational view thereof, the left side elevational view being a mirror image thereof;

FIG. 3 is a top plan view thereof;

FIG. 4 is a front elevational view thereof;

FIG. 5 is a bottom plan view thereof; and,

FIG. 6 is a rear elevational view thereof.
